UNITED STATES PATENT OFFICE.

ELMER E. KEPNER, OF SPRINGFIELD, OREGON.

PEN.

No. 818,258.

Specification of Letters Patent.

Patented April 17, 1906.

Application filed December 18, 1905. Serial No. 292,314.

To all whom it may concern:

Be it known that I, ELMER E. KEPNER, a citizen of the United States, residing at Springfield, in the county of Lane and State of Oregon, have invented certain new and useful Improvements in Pens; and I do declare the following to be a full, clear, and exact description of the invention, such as will enable others skilled in the art to which it applies to make and use the same.

This invention relates to writing-pens; and one of the principal objects of the same is to provide a pen which will hold a quantity of ink at each dipping and which will hold the ink against running out or blotting the paper.

Another object is to provide a writing and manifolding or ruling pen of simple construction which will be strong, durable, and efficient and which can be produced at slight cost.

These and other objects are attained by means of the construction illustrated in the accompanying drawings, in which—

Figure 1 is a perspective view of a pen made in accordance with my invention. Fig. 2 is a plan view of the same. Fig. 3 is a longitudinal section. Fig. 4 is a transverse section on the line 5 5 of Fig. 2, and Fig. 5 is a similar section on the line 4 4 of Fig. 2.

Referring to the drawings for a more particular description of my invention, the numeral 1 designates the shank end of the pen, which may be of any suitable contour, preferably semicircular, to fit an ordinary penholder.

The numeral 2 designates the nibs of the

pen, which may be divided by a slit 3. To form a reservoir for a quantity of ink to be fed to the pen-nibs, the sides of the pen are bent upwardly, forming lips 4, between which the ink is held and permitted to flow only when the pen is in contact with the paper. The pen may be readily supplied with ink by dipping in an ink-well in the usual manner.

Pens made in accordance with my invention may be formed from various materials and will be found efficient as a ruling-pen, a manifolding-pen, or as a non-shading writing-pen of durable construction.

Various changes in the form, proportion, and the minor details of construction may be resorted to without departing from the principle or sacrificing any of the advantages of this invention.

Having thus described my invention, what I claim as new, and desire to secure by Letters Patent, is—

The herein-described pen having upwardly-extending, outwardly-curved lips forming a reservoir between them for the ink, said lips having an inclined front edge and a slit at the converging ends of said lips and a reversely-curved portion to engage a penholder, substantially as described.

In testimony whereof I have hereunto set my hand in presence of two subscribing witnesses.

ELMER E. KEPNER.
